UNITED STATES PATENT OFFICE.

RICHARD L. CRISWELL, OF LAKESIDE, OHIO.

VALVE-LIFTER.

1,384,518.

Specification of Letters Patent. Patented July 12, 1921.

Application filed July 3, 1920. Serial No. 393,899.

To all whom it may concern:

Be it known that I, RICHARD L. CRISWELL, a citizen of the United States of America, and resident of Lakewood, county of Cuyahoga, and State of Ohio, have invented certain new and useful Improvements in Valve-Lifters, of which the following is a specification.

This invention relates broadly to valve lifters, and it has for its primary object to provide an improved form of tool for elevating or compressing the valve-seating springs of internal combustion engines to permit of the ready removal and insertion of the usual spring-retaining pins.

A further object is to provide a tool of the character mentioned which has the spring-engaging portion thereof adjustable to the extent that it is adapted for application to springs and valve stems of any of the various sizes commonly employed.

With these and other objects in view, the invention resides in the features of construction, arrangement of parts and combinations of elements which will hereinafter be exemplified, reference being had to the accompanying drawings, in which—

Figure 1 is a side elevation of the invention showing the same applied in an approximate initial, or entering, position;

Fig. 2 is a top plan view of a preferred form of the lifting bar;

Figs. 3 and 4 are enlarged sections of the same taken, respectively, on lines 3—3 and 4—4, Fig. 2;

Fig. 5 is a fragmentary top plan view of the fulcrum bar;

Fig. 6 is a view similar to Fig. 1, showing a modified construction of the fulcrum element;

Fig. 7 is a similar view illustrating the invention still further modified to adapt it for use in compressing springs in a downward direction; and—

Fig. 8 is an enlarged elevation of the chain-engaging hook shown in Fig. 6.

Referring to said drawings, in which like designating characters distinguish like parts throughout the several views—

A indicates generally the lifting bar which comprises a handle portion 1 and a pair of opposing spring-engaging jaws 2 adapted for application in straddling relation to the stem 3 of a valve 4 and in underlying supporting relation to the stem-encircling valve spring 5. In the preferred embodiment of

the invention, illustrated in Fig. 1, the lifting bar A rests upon a fulcrum bar which is indicated generally by the character B. Said fulcrum bar, which is of approximately 60 semi-cylindrical form in cross-section and which is designed to be positioned with its flat surface uppermost, embodies a handle portion 6 and a flat bifurcated head portion 7, the latter being designed for seating upon 65 a stationary part, as 8, of the engine in straddling relation to the valve stem below the position of the retaining pin 9. Intermediate the head portion 7 and the handle portion 6 is a bend by which the latter is disposed at 70 a suitable downwardly inclined angle to the plane of the former, said bend preferably having an upwardly bowed form, as shown at 10, to provide an arcuately curved seat which constitutes a fulcrum upon which the 75 lifting bar A is rocked for producing the requisite elevation of the valve spring, as indicated in dotted lines in Fig. 1.

A chain 11 having an end attached to the outer end of the bar A depends loosely 80 through an opening 12 provided in the outer end of the bar B. Said chain drops freely through said opening as the outer ends of said bars assume closer relation in the spring-elevating movement, and, when the desired 85 elevation has been effected, said chain is drawn forward into a forwardly extending V-shaped slot 13 in which it will be gripped and firmly held for maintaining the adjusted relation of said bars.

In the modification illustrated in Fig. 6, a hook and chain device is substituted for the bar B. Said device comprises a hook 14 designed to have the point of its bill seat upon a suitable overlying part, as the valve 95 4, for support, and a chain 15 attached to said hook. A hook 16 having an eye portion 17 loosely embracing the lifting bar A is designed to receive and grip any portion of said chain 15 which may be drawn into engagement therewith for supporting said bar during the valve-spring-lifting-operation. As is apparent, the hook 16, which may be adjusted along said bar to any suitable position, constitutes a fulcrum upon which 100 said bar is operated during said lifting operation.

The modified construction above described may also be employed for compressing the springs of downwardly opening valves by 110 interengaging the hook 14 with any suitable stationary part of the engine or engine-sup-

porting frame, as the ledge 23 shown in Fig. 7. Or, for compressing such springs, a further modified construction illustrated in Fig. 7 may be used. In such further modified construction a chain 15^a having a hook 24 at its upper end is looped over the lifting bar A and is adapted to be interengaged with a hook 18 which is attached to the hook 14^a and which has the point of its bill disposed 10 in underlying engagement with the projecting ledge 23.

In its preferred construction, the lifting bar A is formed of a single sheet metal blank and comprises companion members 1^a 15 and 1^b which together constitute the handle portion 1. Each of said members 1^a and 1^b, which are connected at their outer ends by a transverse integral web 19, is of approximate U shape in cross section, and said members 20 are arranged with the parallel sides of the member 1^a received within the embrace of the corresponding sides of the member 1^b, as shown in Fig. 4 so that said members 25 are relatively adjustable telescopically for adjusting the spread of the jaws 2 to suit valve stems or springs of varying sizes. The lifting bar is so formed that the jaw carrying ends of its members normally tend to spread apart a distance adapting the jaws 30 for application to the largest sizes of commercially used springs. A bolt 20 directed through said members adjacent to the jaws 2 carries a wing nut 21 whereby said members may be adjusted toward each other 35 against the resilience tending to hold the same apart, as when application of the bar to springs of smaller size is desired.

The jaws 2 are preferably of L-shape in cross section and have the adjacent edges of 40 the horizontal portions thereof beveled, as shown at 22 in Fig. 3, to facilitate the entering of said portions beneath the springs.

What is claimed is—

1. In a valve lifter, a lifting bar comprising a handle portion composed of connected companion channel members arranged in telescoping relation and terminated at one end by jaws for engagement with a valve spring, means for relatively adjusting said members, and a fulcrum element associated 50 with said bar.

2. In a valve lifter, a lifting bar comprising a handle portion composed of a pair of companion channel members carrying 55 opposing jaws at their front ends, said members being connected adjacent to their outer ends and being disposed laterally in telescopic relation, said members embodying means tending to resiliently maintain the 60 front ends of said members separated for holding said jaws in spread relation, means for telescopically closing said members for adjusting said jaws, and a fulcrum element associated with said bar.

65 3. In a valve lifter, a lifting bar comprising

ing a handle portion having connected relatively adjustable telescoping members terminated at one end by jaws for engagement with a valve spring, and a fulcrum element in underlying engagement with said bar, 70 said element comprising a bar shaped to form a bifurcated head portion and a handle portion, said handle portion being inclined downward from the plane of said head portion.

4. In a valve lifter, a lifting bar comprising a handle portion having connected relatively adjustable companion members terminated at one end by jaws for engagement with a valve spring, and a fulcrum element 80 associated with said bar, said element comprising a bar shaped to form a bifurcated head portion, a handle portion and an upwardly bowed portion intermediate said head and handle portions, said handle portion being downwardly inclined from the plane of said head portion, and the convex face of said bowed portion constituting a seat upon which said lifting bar is fulcrumed.

5. In a valve lifter, a lifting bar comprising a handle portion having connected relatively adjustable companion members terminated at one end by jaws for engagement with a valve spring, and a fulcrum element 90 associated with said bar, said element comprising a bar shaped to form a bifurcated head portion, a handle portion and an upwardly bowed portion intermediate said head and handle portions, said handle portion being downwardly inclined from the plane of said head portion, and the convex face of said bowed portion constituting a seat upon which said lifting bar is fulcrumed, and means whereby the outer 95 ends of said bars may be secured in adjusted relation.

6. In a valve lifter, a lifting bar comprising a handle portion having connected relatively adjustable companion members terminated at one end by jaws for engagement with a valve spring, and a fulcrum element 110 associated with said bar, said element comprising a bar shaped to form a bifurcated head portion, a handle portion and an upwardly bowed portion intermediate said head and handle portions, said handle portion being downwardly inclined from the plane of said head portion and having a slot in the outer end portion thereof, and a chain depending from the lifting bar and adapted 115 to be seated in said slot for securing said bars in adjusted relation.

In testimony whereof, I affix my signature in presence of two subscribing witnesses.

RICHARD L. CRISWELL,
